UNITED STATES PATENT OFFICE.

WILLIAM HENRY REED, OF SERVIA, INDIANA.

FARM-FENCE.

SPECIFICATION forming part of Letters Patent No. 321,531, dated July 7, 1885.

Application filed June 2, 1884. (No model.)

To all whom it may concern:

Be it known that I, WILLIAM H. REED, a citizen of the United States, residing at Servia, in the county of Wabash and State of Indiana, have invented certain new and useful Improvements in Farm-Fences; and I do hereby declare that the following is a full, clear, and exact description of the same, reference being had to the annexed drawings, 10 making a part of this specification, and to the letters and figures of reference marked thereon.

Figure 1 of the drawings is a perspective view of a fence constructed in accordance with my invention; Fig. 2, a side elevation of that 15 portion of the fence supported by the stakes; Fig. 3, an end view, with the rails in section; and Fig. 4, a detail view in section, showing the manner of securing the rails to the end post.

The present invention has relation to that 20 class of fences in which are employed cross-braces and binders, the rails being placed alternately one above the other and connected to the braces and binders by wire.

Previous to my invention it was common to 25 secure the fence-rails in position by looping the wire around the upper extremities of the cross-braces and binding-stake, bringing it between and over the two upper or rider rails, thence carrying the wire down and around the 30 ends of the remaining rails and fastening the end of the wire to the lower end of the stake, the wire being also secured at different points thereto and to the cross-braces by independent pieces of wire looped around the same.

In the construction of fences to render them 35 strong and firm, it was also common to employ short pieces of wire secured around the cross-braces above and below the upper or rider rail, also around the binding-stakes, and 40 diagonal braces arranged upon the sides of each fence-panel.

It is the object of this invention to improve 45 the above-described manner of securing the rails in position to the cross-braces and binders; and it consists in the peculiar manner of fastening the wire around the rails, cross-braces, and binders, substantially as shown in the drawings, and hereinafter described and claimed.

50 In the accompanying drawings, A represents one of the end posts, B the lower rails, and C the upper or rider rails overlapping

each other at their meeting ends and supported by the cross-braces D, secured at their lower ends in the ground.

55

The inner sides of the posts A are formed with a series of mortises, a, in which fit the ends of the rails B C. In forming these mortises, if preferred, slits b may extend across the posts, of a depth equal, or nearly so, to the 60 depth of the mortises, so as to allow the sides thereof to yield when driving in the ends of the rails, after which the rails are further secured in the mortises by suitable fastenings, c.

The upper ends of the cross-braces D are 65 connected and held together by a wire loop, d; and there are also connected to the upper end of one of the cross-braces, by a similar loop, e, binders E, between which the ends of the rails B C are located. The binders E are tightly 70 drawn against the sides of the rails B, where they overlap each other, by wire loops f g, the upper loop, f, simply passing between the rails and around the binders, while the lower loop, g, extends around two of the rails and also 75 around the binders, as shown more clearly in Fig. 3. A truss-wire, h, is first passed under the lower rail, and thence brought upward over the upper one of the rails B, at which point the wire is crossed upon itself and the rails 80 drawn tightly together, and the ends of the wire passed around the two upper rails, C, and fastened. By the employment of the trussing-wire h the rails are drawn together—the lower ones in an upward direction, and the upper 85 ones, C, in a downward direction, in both instances the rails being drawn against the stakes at points above and below where they cross each other.

It should be understood that the mortises a 90 in the fence-post A, with the exception of the upper one, are disposed a distance apart equal, or nearly so, to the thickness or width of the rails, so that when they are connected to the post the ends of the rails will form supports 95 for the ends of the rails opposite, and vice versa.

The manner of securing the rails by the trussing-wire, and the employment of the hangers, in addition to the wire loops used, 100 form together a very strong and durable farm-fence, when taken in connection with the posts, cross-braces, and rails, hereinbefore described.

In a fence constructed in accordance with

my invention there is no danger of the rails becoming loose and dropping down, and the expense required in building such a fence is materially decreased.

5 Having now fully described my invention, what I claim as new, and desire to secure by Letters Patent, is—

In a farm-fence, the cross-braces and binders thereof, in combination with wire loops connecting the braces together at their upper ends, loops securing the binders to the braces and holding them against the sides of the fence-rails, as shown, and a trussing-wire extending

under the lower rail, and thence upward to a point where the braces cross each other, where 15 the said wire is crossed and brought over the two upper or rider rails in opposite directions and fastened, substantially as and for the purpose set forth.

In testimony that I claim the above I have 20 hereunto subscribed my name in the presence of two witnesses.

WILLIAM H. REED.
